HUMIDIFIER

Edward M. Stolarz, New York, N.Y., assignor to Walton Laboratories, Inc., Irvington, N.J., a corporation of New Jersey

Filed Sept. 14, 1961, Ser. No. 66,779

Term of patent 14 years

(Cl. D62—4)

FIG. 1 is a top plan view of a humidifier, showing my new design;

FIG. 2 is a side elevation thereof; and

FIG. 3 is a longitudinal section view taken along the line 3—3 in FIG. 2.

The bottom of the humidifier is substantially flat and plain.

The dominant features of my design reside in the portions shown in full lines in the drawing.

I claim:

The ornamental design for a humidifier, as shown and described.
